TOWEL DISPENSING APPARATUS

Jacob A. Hunkele, Pittsburgh, Pa.

Application September 19, 1933, Serial No. 690,049

5 Claims. (Cl. 312—37)

This invention relates to individual towel dispensing devices by which individual towels can be supplied successively to respective users without however permitting their detachment from the cabinet mechanism by the user, thus preventing unauthorized carrying away, mislaying or other loss of the same.

The principal object of the invention is to provide a novel construction and arrangement of the towel supporting member and stringer which prevents the removal of the towels from the dispenser while permitting them to be freely and conveniently used.

Another object of the invention is to provide novel means from which a towel may be drawn a sufficient distance from the dispenser to permit convenient use.

Still another object of my invention is to provide a novel arrangement to prevent the unauthorized use of clean towels, if so desired.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a perspective view of a towel dispensing device showing the door opened up to show part of the interior of the clean towel compartment and as it would be for the purpose of loading or unloading a stack of towels, having part of the front of the lower compartment broken away.

Figure 2 is a vertical sectional side elevation embodying the invention, showing in full lines a towel ready for use and in dot and dash lines a towel also ready for use but farther away from the cabinet.

Figure 3 is a front view on an enlarged scale of the clean towel compartment, with portions broken away, the door being open and showing the method of preventing removal of clean towels, if so desired.

Figure 4 is a perspective view of the upper compartment of the dispenser, ready for use with the lower portions of the cabinet broken away.

Figure 5 is a detail perspective view of the locking shield as shown in Figure 4.

Figure 6 is a sectional view of the towel supporting member and associated parts.

Figure 7 is a perspective view of the rear end portion of the tubular member containing the pull-rod and spring.

Figure 8 is a perspective view of the rear end portion of the towel supporting member.

Figure 9 is an end view of Figure 6.

Figure 10 is a perspective view showing the means of locking the retaining rod in the lower compartment of the cabinet.

Figure 11 is a vertical sectional view taken along and near the hinged side of the door opening in Figure 3.

In general, the apparatus comprises a cabinet 10 11 as shown in Figures 1 and 2 and is preferably made in two separate sections, the upper section 12, forming a compartment for hanging clean towels, and a lower section 13, forming a compartment for holding soiled towels. Said upper 15 section 12 is provided with a hinged top cover 14 and a hinged front door 15 for closing the latter and for convenient opening to permit access to the interior of the cabinet.

As shown in Figure 2 a series of clean towels 20 16 are provided and having gromets 17 near one end and at the middle of the towels and a tubular towel supporting member 18 is inserted through said gromets to string the towels thereon.

This towel supporting member 18 is detachably secured to the middle portion of the rear wall 19 of the clean towel compartment by means of a forked wall-plate 20 and the free end of said towel supporting member 18 extends to the bottom of the soiled towel compartment and is 30 inserted into a suitable fastening and locking means, such as shown in Figure 10.

In Figures 6, 7, 8 and 9 I have shown detailed views of the towel supporting member 18 and the towel retaining rod 21. The towel supporting member consists of a tubular outer member 22 provided at its rear end with a pair of oppositely disposed short slots 23 for the reception of the holding lug 24 which is pivotally fixed to the rear end of the tubular pull-rod container 25 40 as illustrated in Figure 7. The foremost ends of said outer member 22 and the pull-rod container 25 are turned inwardly as indicated by the numerals 26 and 27.

The portion of the towel retaining rod 21 is 45 permanently and rigidly attached to the pull-rod 28. This pull-rod 28 is of a smaller cross-section than said retaining rod 21 and the extreme rear end thereof is provided with an enlarged head 29 which retains the compression coil spring 30 within the pull-rod container 25.

The forward end of the towel retaining rod 21 is bent forwardly along a gradual curve as indicated at 31 and then bent downwardly and rearwardly as at 32 and down into the lower 55

soiled towel compartment 13. A circular collar 33 is welded on the outer tubular member 22 near the rear portion thereof, so as to provide a rest against the inner face of the forked portion of the wall-plate 20 when in a position as shown in Figure 2.

As previously stated, the pull-rod container 25 is provided at its rearward end with a pivoted holding lug 24 which engages when locked 10 the slots 23 of the outer member 22, so as to prevent rotation of said pull-rod container 25 in said outer member 22.

In describing the operation of the device it is assumed that there is a stack of clean towels 15 16 in place and that it is otherwise in readiness for use (see Figure 4). The towels prior to loading, have had their lower ends folded upwardly and the lower edge of the foremost towel is positioned in front of the slotted opening 34 20 below the lower edge of the front door 15. In order to more conveniently reach a towel said lower edge of said front door 15 is provided with a central cut-out portion 35.

A person desiring to use a towel grasps the 25 foremost towel through cut-out portion 35, pulls it forward on the retaining rod 21 to a position convenient for use, where it can be used for the hands or face.

Since the towels must be small enough to 30 make it commercially feasible to use them once only it has been found that it will greatly add to the convenience of the user, for instance, when wiping the face if the towel can be drawn away from the container as much as possible 35 and thereby eliminate the objection where the person is obliged to put his head too close to the container in order that the towel may be used on the face. This may conveniently be accomplished by constructing the towel supporting member 18 and the towel retaining rod 21 40 as heretofore described and which is best illustrated in Figures 2 and 6, so as to provide a towel retaining rod which may be extended outwardly and yet extend, when in normal position, 45 from the cabinet at a minimum distance.

Previously chains or thin flexible wires have 50 been used as a means for retaining the towels, but it has been found in practice that these materials are not as suitable as a stiff rigid retaining rod, especially when using sewed gromets on the towel instead of metal gromets.

A thin flexible wire will in time break very 55 easily or it may be pinched off with a pair of pincers, a chain will not permit a towel provided with a sewed gromet to slide down freely into the soiled compartment after using and a fixed and rigid retaining rod of the old construction will not give the user entire freedom of movement and generally he assumes an unnatural position while wiping his face, since the exposed part of the retaining rod must be reduced to a minimum for obvious reasons. In my invention the towel retaining rod 21 (Figure 6) may be drawn outwardly by slightly pulling the towel while using, this action compresses the spring 30, thus permitting the retaining rod to assume a position as shown in dot and dash lines in Figures 2 and 6.

When the supply of towels 16 is exhausted the 70 procedure to replenish them is as follows: Padlock 36 in soiled towel compartment is removed and the lower free end of the retaining rod 21 is disengaged from the spring-clamp 37, the towel supporting member 18 is then lifted out of 75 engagement of the forked wall plate 20 and re-

moved from the cabinet. By pushing the retaining rod 21 rearwardly the holding lug 24 becomes disengaged from the slots 23 of the outer member 22. By turning the holding lug 24 into a position as shown in Figure 7 the retaining rod 21 and the pull-rod container may now be withdrawn from said outer member 22. After this is accomplished a fresh supply of towels is placed on said outer member 22, the retaining rod 21 including the pull-rod container is again 10 inserted into the outer member 22 and locked in position by turning the holding lug 90 degrees (Figs. 6 and 9). The retaining rod 21 is then brought in alignment with the slots 23 of the outer member 22 and pushed forwardly so as 15 to again engage said slots 23. The towel supporting member 18 is again placed in the clean towel compartment in a manner previously described. This brings the apparatus to normal condition ready for use.

In order to prevent the use of towels after or before working time, I provide a shield 38 (Figures 1, 3, 4 and 5) preferably made of sheet material, which is pivotally mounted under the lid 14 and retained, when not in use, in a position as 25 best shown in Figures 3 and 4 (full lines) by means of a catch-lug 39 engaging with a suitable catch or holding device 40 attached to lid 14. Said shield 38 consists of a tapered narrow portion 41 and an enlarged rounded portion 42 and 30 having an open downwardly directed slot 43.

To prevent removal of towels the shield 38 is lifted out of engagement of catch 40 and swung down into a position shown in dot and dash lines in Figures 3 and 4. A suitable cleat 44 is 35 securely attached to the inner wall 45 in line with the edge of the slotted opening 34 of the cabinet front so as to permit the rounded portion 42 of said shield 38 to penetrate into the open space 46 of said cleat 44. In that position the 40 slot 43 of shield 38 surrounds the towel retaining rod 21. As the door 15 of the cabinet is closed the pin 48 which is fastened to the inner face of 45 said door 15 engages the aperture 49 of shield 38.

This arrangement positively prevents removal of towels, if so desired, and does not interfere with the placing or removal of towels when the shield 38 is in an "up" position.

The device as described may be supplemented 50 by coin controlled mechanism, so that its use shall depend on the insertion of a coin in a slot.

While I have illustrated and described with 55 particularity only a single form of my invention, I do not desire to be limited to the exact structural details thus illustrated and described; but intend to cover all forms and arrangements which come within the terms employed in the definitions of my invention constituting the appended claims.

I claim:

1. In a device for supporting towels and the like having a gromet, an outer tubular support adapted to be engaged by said gromets, an inner tubular support within said outer tubular support, means to prevent rotation of the inner tubular 65 support within said outer tubular support, a towel retaining rod having a part coaxially disposed within said tubular supports and means to retract said part of the towel retaining rod within said inner tubular support.

2. In a device for supporting towels and the like having a gromet, an outer tubular support adapted to be engaged by said gromets, an inner tubular support within said outer tubular support, means to prevent rotation of the inner tubular 75

support within said outer tubular support, a towel retaining rod having a part coaxially disposed and slidable and rotatable within said tubular supports and means to retract said part of the 5 towel retaining rod within said inner tubular support.

3. In a device for supporting towels and the like having a gromet, an outer tubular support adapted to be engaged by said gromets, an inner tubular support within said outer tubular support, 10 means hingedly mounted in said inner tubular support to prevent the rotation thereof with the outer tubular support, a towel retaining rod having a part coaxially disposed and slidable and rotatable within said tubular supports and means 15 to retract part of the towel retaining rod within said inner tubular support.

4. In a device for supporting towels and the like having a gromet, an outer tubular support adapted to be engaged by said gromets, an inner tubular support within said outer tubular support, 20 means hingedly mounted in said inner support to prevent the rotation thereof with the outer

tubular support, a towel retaining rod having a part coaxially disposed and slidable and rotatable within said tubular supports and comprising a reduced extension extending within said inner tubular support, a spring element surrounding said reduced extension and an abutment knob for said spring element on the end of said reduced extension.

5. In combination with a cabinet for dispensing 10 towels provided with an opening for inserting and extracting towels, a lockable door for said opening of lesser height than said opening adapted to provide at the bottom thereof a slot for dispensing towels; a towel support; means within said cabinet adapted to prevent removal 15 of towels from said towel support and through said dispensing slot, said means comprising a pivotally mounted, depending shield having an enlarged free end which is provided with a slot adapted to surround said towel support when in 20 locked position and means to retain said shield in locked position.

JACOB A. HUNKEL.
